MEANS FOR LUBRICATION OF PINTLE AND HINGE SECTIONS OF PRUNING SHEARS

Filed April 21, 1930

INVENTOR.
GEORGE F. HICKOK.

BY *James Griffith,*
ATTORNEY.

UNITED STATES PATENT OFFICE

GEORGE F. HICKOK, OF BURLINGAME, CALIFORNIA

MEANS FOR LUBRICATION OF PINTLE AND HINGE SECTIONS OF PRUNING SHEARS

Application filed April 21, 1930. Serial No. 445,908.

The present invention relates to means for the lubrication of pintle and hinge sections of shears, and more particularly to those parts of pruning shears.

5 As is very well known, the present practice in lubricating pintle and hinge sections of pruning shears is to dip the entire blades including the hinged sections in a vessel of oil allowing these to remain immersed there-
10 in for such time as may be required to effect a complete oiling, this requiring no little time and attendant annoyance.

The present invention has for its object the provision of a lubricant stored in a hollow pintle containing therewithin an absorbent adapted for saturation with the lubricant and provided with a port, or opening, for the exudation therethrough of the lubricant to the pintle's exterior surface and
20 thence carried to the surrounding frictional engaging surfaces of the blades through ducts, or channels, carried radially and superficially by one or the other, or both, of the frictionally engaged blade surfaces.

25 Though intended primarily for the lubrication of the hinged sections of pruning shears, it is obvious that the same lubricating system may be applied to any and all shears depending upon the crossing of their blades
30 for their shearing action, upon applying compression.

In the accompanying single sheet of drawings, forming a part of this specification, and in which similar reference characters re-
35 fer to like parts, throughout:

Figure 1 is a plan view of a pair of pruning shears showing a shock-absorber in place and with the handles partly broken away.

40 Figure 2 is an end elevation of the blades, with the hinged portion sectioned for the better illustration of the pintle and its hollowed section bearing the oiler.

Figure 3 is a longitudinal sectional view of the pintle, including its bore extending
45 partly therethrough and its contained oiling member.

Figure 4 is a plan view of the head borne by one extremity of the pintle and as an integral part thereof.

50 Figure 5 is a plan view of the interior of a

blade section, showing the opening therethrough for the accommodation of the pintle and the oil ducts, or channels, radiating therefrom for oil distribution.

Referring more particularly to the drawings, the numeral 3 refers, in a general way, to a pair of pruning shears, of which 4 and 8 are the blades, the one being properly the blade and the other the hook, the blade being provided with a bevelled section 5, body extensions 6 and 9 adapted to be secured to wooden handles 7 and 10, shown on the drawings as partly broken away, and a means for hingedly uniting the blades, comprising registering blade-holes, one of which is threaded and adapted to accommodate the threaded end of the pintle, said pintle being provided with an hexagonal head 16 as an aid in screwing it into the said blade-opening, and a locking nut 14 adapted to be set-up on the free threaded end of the pintle against the surface of the blade, or hook, 8, the pintle being further provided with a bore 19 extending longitudinally from its hexagonal head to approximately half its length, its purpose to be made apparent later.

The oiling feature 21, as indicated in Figure 3, comprises a hollow cylindrical member 12 mounted in the bore 19, provided with a valve-seat 13 and an orifice 18 extending through both its wall and the contiguous wall of the pintle bore. Surrounding the region of said orifice, there is placed a layer of oil-absorbing material 23 and resting upon this a spiral spring 17 bearing a hemispherical valve 15 adapted through the urge of the spring 17 to remain seated upon the valve seat 13 carried by the upper end of the cylindrical member 12. To facilitate the oil distribution to the exterior surface of the pintle and to the contacting surfaces of the blades approximate thereto, the inner surface of the blade 4 is provided with a plurality of oil channels radiating outwardly from the blade opening 20.

Considering the space surrounding the spring 17 as the oil reservoir, and that it is desired to replenish the oil supply, an oil-can spout is applied to the valve 15 to force it down and the oil forced into the reservoir

until replenished, when, upon removal of pressure against 15 it immediately seats, for the retention of the oil and the exclusion of dirt, and with lubrication of pintle and adjacent parts taking place from the saturated material 23 through the orifice 18 and the distributing channels 22.

Having thus described my invention, I claim, and desire to secure by Letters Patent of the United States, the following:

1. In a pruning device of the character described, pruning members having registering openings near the bases of the blades thereof, a hollow pintle positioned in said openings having an orifice in the wall thereof and serving as a pivotal connection for said blades, the frictional surface about the opening of one of said blades bearing a plurality of channels for the conveyance of a lubricant, an absorbent substance within the hollow pintle for the retention of said lubricant, said pintle being provided with a filling opening leading to said bore.

2. A pruning device comprising a pair of blades having frictional engaging faces, each of said blades having an opening therethrough and terminating in its friction face, a pintle member extending through said openings, one of said blades having a plurality of grooves on its friction face radiating outwardly from the opening therein, said pintle having a bore therein and an orifice leading from said bore through the wall of the pintle and in the plane of the grooves in the blade, and a lubricant in said bore.

In testimony whereof I hereunto affix my signature.

GEORGE F. HICKOK.
